FLEXIBLE HANDRAIL AND SUPPORT THEREFOR

Filed March 29, 1929

INVENTOR:
WILLIAM O. HARTMAN

15 BY Arthur C. Ecock

ATTORNEY.

UNITED STATES PATENT OFFICE

WILLIAM O. HARTMAN, OF ST. LOUIS, MISSOURI, ASSIGNOR TO WELSH-HARTMAN CO.,
OF ST. LOUIS, MISSOURI, A CORPORATION OF MISSOURI

FLEXIBLE HANDRAIL AND SUPPORT THEREFOR

Application filed March 29, 1929. Serial No. 350,958.

The object of my device is to make a flexible hand rail and support therefor, to be used principally on the walls adjacent staircases, for the usual manual support purposes.

A further object is to make a device of the character described particularly for the use of infants in walking on stairs. When the device is used for infants, it is placed low enough to be within their manual grasp.

A further object is to support the flexible rail on brackets, the brackets being so constructed that one type may be used to support the rail at all its terminal and intermediate supports.

A still further object is to so make the support that the rail holding portion may be selectively adjusted in position.

My device may be easily and simply made of few and simple parts that lend themselves readily to multiple production, may be cheaply made and are extremely compact for packing. With these and other objects in view my invention has relation to certain novel features of construction and arrangement of parts, as will be hereinafter more fully described, pointed out in the claims and illustrated in the drawings in which

Fig. 1 is a side elevation of a staircase with my flexible hand rail support attached to the adjacent wall in operative position.

Fig. 2 is a sectional elevation of a portion of the flexible rail such as rope or wire with buttons shown, which may be slidably secured on the flexible rail.

Fig. 3 is a side elevation of the plate, a bracket and rail support.

Fig. 4 is a front elevation of the plate, bracket and rail support.

Numeral 5 designates the flight of stairs with the upper and lower elevations 6 and 7 and the intermediate platform 8. Numeral 9 designates the side wall adjacent the flight of stairs 5. Numerals 10, 11, 12 and 13 designate the rail supports generally. These supports consist of the plate 14, which is secured

to the side wall 9 by means of screws passing through the holes 15. Numeral 16 designates a bracket, which is secured to the plate 14 by means of the rivets 17. Numeral 18 designates a pipe section, which is secured to the bracket 16 to its outermost face by means of the bolt 19, which passes through the hole 20 in the pipe section 18 and the hole 21 in the bracket 16. The head of the bolt is slotted at 22 for the reception of a screw driver. Numeral 23 designates a nut in threaded engagement on the inner end of the bolt 19. In order to have access to the slotted head 22 of the bolt 19, the hole 24 is formed in the pipe section 18 diametrically opposite and concentrically to and with the slotted head 22. The bolt 19 is secured in such a manner that the pipe section 18 may be rotated on it. Numeral 25 designates the flexible hand rail, which may be made of rope or wire etc. After the hand rail supports 10, 11, 12 and 13 are secured, as shown in Fig. 1, the flexible hand rail 22 is secured thereto by passing it through the pipe section 18 on each rail support. For purposes of ornamentation or making the flexible hand rail larger in diameter, the buttons 26, which have the holes 27 formed therein longitudinally, may be slid over the flexible hand rail 25 between the hand rail supports 10, 11, 12 and 13.

It will be seen that the pipe section 18 owing to its pivotal contact with the bracket 16 will position itself, as shown in the hand rail supports, 10, 11, 12 and 13. For this reason it is only necessary to have one type of hand rail support for all the supports of the hand rail, instead of different types depending on the angle that the flexible hand rail forms with the plate 14 of the rail support.

What I claim and mean to secure by Letters Patent is:

1. A flexible hand rail having buttons slidably secured thereon, a support, said hand rail secured in said support.

2. A hand rail support comprising a plate, a bracket secured to said plate, a pipe section having a hole in its lateral surface, a bolt having a slotted head passing through the hole in said pipe section, said bolt passing through a hole in said bracket, so as to pivotally secure said pipe section to said bracket, a hole formed in said pipe section opposite the slotted head of said bolt, a flexible hand rail passing through said pipe section, buttons in sliding engagement on said flexible hand rail.

In testimony whereof I affix my signature.

WILLIAM O. HARTMAN.
